UNITED STATES PATENT OFFICE.

WILLIAM A. PALMER, OF ENSLEY, ALABAMA.

CAR-COUPLING.

SPECIFICATION forming part of Letters Patent No. 734,935, dated July 28, 1903.

Application filed April 17, 1903. Serial No. 153,134. (No model.)

To all whom it may concern:

Be it known that I, WILLIAM A. PALMER, a citizen of the United States, residing at Ensley, in the county of Jefferson and State of Alabama, have invented certain new and useful Improvements in Car-Couplers; and I do hereby declare the following to be a full, clear, and exact description of the invention, such as will enable others skilled in the art to which it appertains to make and use the same.

My invention relates to improvements in automatic car-couplers of the Janney type, wherein the coupling-knuckle is both opened and held closed by the locking-pin arrangement, the locking-pin and its attachment being so constructed and coöperating with the coupling-knuckle as to open the same when elevated and be supported in its elevated position by the coupling-knuckle until the same is returned to its closed position and locked by the release and gravitation of the pin.

To more fully describe my invention, reference is had to the accompanying drawings, in which like letters refer to corresponding parts in the several views, and in which—

Figure 1 is a plan view of my improved coupler; Fig. 2, a similar view, the coupler-head being shown in horizontal section on the line 2 2 of Fig. 3; Fig. 3, a vertical transverse section on the line 3 3 of Fig. 2; Fig. 4, a perspective view of the coupling-knuckle, and Fig. 5 a perspective view of the locking-pin and its attachment.

A is the ordinary hollow draw-bar of this style coupler provided with the enlarged head cast hollow to form a chamber for the reception of the operating parts. The hollow head has the vertically-disposed rounded internal rib or shoulder A', adapted to fit the curved rear edge of the knuckle-tailpiece, hereinafter described.

On the top of the coupler is formed the housing A³, slotted at A⁴ to receive and guide the locking-pin and attachment, and the lower face of the coupler-head is also slotted, as at A², Figs. 2 and 3, for the reception of the lower end of the locking-pin attachment.

B is the coupling-knuckle, pivoted at C to the hollow draw-head and provided with a

tailpiece comprising the toe-member portion B' and the heel B². This tailpiece, as clearly shown in Fig. 4, is curved on its outer edge face B⁰ to closely fit the rounded rib A' of the coupling-head and is straight on its inner edge face b to engage the coupling-pin when the knuckle is closed, the heel portion B² being beveled on its upper face b' and rounded on its lower surface b².

D is the coupling-pin, preferably substantially triangular in cross-section, having the straight side faces d d' and the curved front face d⁰, adapted to engage a correspondingly curved shoulder formed in the hollow draw-head. Means for raising the coupling-pin may be suitably secured through the aperture d².

Pivottally suspended at its upper enlarged end E' to the pin D by means of the pivot-pin F and split pin G is an attachment or member E, which I have termed the "knuckle-opener," in exterior contour somewhat similar to the figure 5. The upper portion of this swinging knuckle-opener is substantially L-shaped and provided with a hook or tailpiece curving downwardly, as at E⁰, from the point E³ and projecting inwardly at its lower end to form the finger E². The inner face of the finger E² is curved upwardly, forming the cam-surface E¹, until it meets the lower beveled edge e' of the shoulder e. The lower beveled face of the shoulder e projects a short distance below the coupling-pin D. The locking-pin and knuckle-opener are formed with flanges or shoulders d^x e^x, which rest on the top of the housing A³ and support them thereon. The locking-pin when the parts are assembled is inserted through top slot of the coupler-head and the shank end of the knuckle-opener through the bottom slot A².

The operation is as follows: In its normal closed position, Figs. 2 and 3, the coupling-knuckle B is securely locked by the face d⁰ of the locking-pin engaging the face b of the knuckle-tailpiece, the shoulder of the knuckle-opener resting against the inner face of the heel B² and the curved portion B⁰ of the tailpiece resting snugly against the rounded rib A'. As the pin D is raised to uncouple

when the shoulder e passes beyond the heel B^2 the weighted finger E^2 gravitates downwardly and inwardly, the beveled edge e' resting on the beveled edge b' of the heel B^2 .

- 5 As the operation is continued the curved portion or cam-face e^2 rides against the curved face b^2 of the heel B^2 and swings the coupling B open, the pin D when the coupling-knuckle is in its open position resting on the toe portion B' , and it is retained in its elevated position until the coupling-knuckle is again closed, when the heel B^2 engages the side face of the shoulder e , swings the knuckle-opener E outwardly, and allows the pin D to drop in position to lock the coupling-knuckle.

It will be observed that the lower edge e' of the shoulder e is slightly below the lower edge of the pin D ; otherwise the heel B^2 when swung inwardly would pass beneath the beveled edge e' of the shoulder e and prevent the pin D from dropping down. Thus it will be seen that I provide a simple and effective means for both automatically opening the coupling-knuckle when the locking-pin is raised and locking the same upon its return to the closed position.

Although I prefer the construction and arrangement of parts as herein described, it is obvious that modifications might be made without departing from the spirit of my invention, and

Having thus described my invention, what I claim, and desire to secure by Letters Patent of the United States, is—

- 35 1. In a car-coupler the combination with the pivoted coupling-knuckle, of a locking-pin adapted to be moved and rest on said knuckle when in its open position, and a member pivotally mounted on and normally suspended alongside said locking-pin having a cam-face adapted to engage said knuckle when the locking-pin is moved upwardly.

2. In a car-coupler the combination with the pivoted coupling-knuckle, of a tailpiece 45 on said knuckle, a locking-pin adapted to be moved and rest on said tailpiece when the coupling-knuckle is in its open position, and a member pivotally carried by and normally suspended alongside of said locking-pin having a cam-surface adapted to engage said tailpiece when the locking-pin is moved upwardly.

3. In a car-coupler the combination with the pivoted coupling-knuckle, of a tailpiece 55 formed integral with and disposed centrally of said knuckle in a horizontal plane, a locking-pin adapted to be moved and rest on said tailpiece when the coupling-knuckle is in its opened position, and a member pivotally mounted on and normally suspended alongside said locking-pin having a cam-face adapted to engage said tailpiece when the locking-pin is moved upwardly.

4. In a car-coupler, the combination with

the pivoted coupling-knuckle, of a tailpiece 65 on said knuckle provided with a heel portion, a locking-pin adapted to be moved and rest on said tailpiece when the coupling-knuckle is in its open position, and a member carried by said locking-pin having a cam-surface 70 adapted to engage said heel when the locking-pin is moved upwardly.

5. In a car-coupler, the combination with the pivoted coupling-knuckle, of a tailpiece on said knuckle provided with a heel portion, 75 a locking-pin adapted to be moved and rest on said tailpiece when the coupling-knuckle is in its open position, and a member carried by said locking-pin having a curved cam-surface adapted to engage said heel when the locking-pin is moved upwardly.

6. In a car-coupler the combination with the pivoted coupling-knuckle, of a tailpiece provided with heel and toe portions, a locking-pin adapted to be moved and rest on said 85 toe portion when the coupling-knuckle is in its open position, and a member carried by said locking-pin having a cam-surface adapted to engage said heel portion when the locking-pin is moved upwardly.

7. In a car-coupler the combination with the pivoted coupling-knuckle, of a tailpiece carried by said knuckle and provided with a projecting heel, a locking-pin adapted to be moved and rest on said tailpiece when the 95 coupling-knuckle is in its open position, and a pivotally-mounted hook member carried by said pin, provided with an inwardly-projecting shoulder and a finger extending below said shoulder having a curved cam-surface 100 adapted to engage said heel when the locking-pin is moved upwardly.

8. In a car-coupler the combination with the pivoted coupling-knuckle, of a tailpiece carried by said knuckle provided with a projecting heel beveled on its upper face, a locking-pin adapted to be moved and rest on said tailpiece when the coupling-knuckle is in its open position, a hook member pivotally suspended on said pin, a finger forming the 110 curved end of said hook member and adapted to engage said projecting heel when the locking-pin is moved upwardly, and an inwardly-extending beveled shoulder formed above said curved finger.

9. In a car-coupler the combination with the pivoted coupling-knuckle, of a tailpiece provided with a projecting heel portion rounded on its lower surface, a locking-pin adapted to be moved and rest on said tailpiece 120 when the coupling-knuckle is in its open position, and a member carried by said locking-pin having a curved cam-surface adapted to engage said rounded heel portion when the locking-pin is moved upwardly.

10. In a car-coupler the combination with the hollow draw-head provided with an internal vertically-disposed rounded rib or projec-

tion, a coupling-knuckle pivoted in said draw-head adjacent said vertical rib, a tailpiece on said knuckle provided with a toe portion curved to fit snugly around said vertical rib, 5 a locking-pin adapted to be moved and rest on said toe portion when the coupling-knuckle is in its open position, and a member carried by said locking-pin adapted to engage said

tailpiece and swing said knuckle open when the pin is moved upwardly.

In testimony whereof I affix my signature in presence of two witnesses.

WILLIAM A. PALMER.
